UNITED STATES PATENT OFFICE.

ROBERT H. INGERSOLL, OF NEW YORK, N. Y.; CHARLES S. SMITH, OF LANSING, MICHIGAN, AND FREDERIC C. LEUBUSCHER, OF ESSEX FALLS, NEW JERSEY, EXECUTORS OF SAID ROBERT H. INGERSOLL, DECEASED, ASSIGNEES TO ROBT. H. INGERSOLL, INC., OF NEW YORK, N. Y., A CORPORATION OF NEW YORK.

MECHANICAL PENCIL.

Application filed May 1, 1926. Serial No. 106,022.

The invention relates to new and useful improvements in mechanical pencils, and more particularly to the mechanism for advancing the lead and for locking the lead 5 when positioned for writing.

An object of the invention is to provide a mechanical pencil of the above type with mechanism adapted to feed the lead forward, and to grip the lead and lock the same 10 when in position for writing, said gripping means operating to engage and lock the lead when the feeding mechanism is at the forward end of its movement.

A further object of the invention is to 15 provide a mechanical pencil of the above type wherein the lead is fed forward by means which frictionally engages the lead, and wherein said frictional means is forced into locking engagement with the lead when 20 said feeding mechanism is at the forward end of its stroke.

A further object of the invention is to provide a mechanical pencil of the above type, with means for gripping the lead when 25 the feeding mechanism is retracted so that a new length of lead can be fed forward on the forward movement of said feeding means.

A still further object of the invention is 30 to provide a feeding and locking means for the lead of the above type, wherein said feeding and locking means is operated by a screw which holds the locking means in firm gripping engagement with the lead.

35 These and other objects will in part be obvious and will in part be hereinafter more fully disclosed.

In the drawings—

Figure 1 is a sectional view through the 40 mechanical pencil embodying my improvements with the lead fed forward and clamped in writing position;

Fig. 2 is a similar view but showing the feeding means and clamping means re- 45 tracted;

Fig. 3 is a view partly in side elevation and partly in section through the outer casing showing the feeding and clamping means in retracted position;

50 Fig. 4 is a view partly in section and partly in side elevation showing a slightly modified form of the invention and with the lead clamped in writing position;

Fig. 5 is an enlarged sectional detail lengthwise of the pencil shown in Fig. 4, but 55 with the clamping and feeding means retracted;

Fig. 6 is a view similar to Fig. 1, but with a modified form of means for moving the inner casing lengthwise for the feeding and, 60 clamping of the lead; and

Fig. 7 is an enlarged sectional view transversely of the body of the pencil midway between the length of the tapered portion thereof. 65

The invention is directed broadly to a mechanical pencil which is provided with a magazine in which the leads are to be stored, and this magazine has the end thereof adjacent the writing end of the pencil formed 70 cone-shaped, and centrally of the cone-shaped end is a passage through which the lead is directed to writing position. The writing end of the casing of the pencil is tapered to a point and has an opening 75 through which the lead is to be projected. In the tapered end of the casing there is a split sleeve, and the lead passes through this split sleeve. Means is provided for forcing the split sleeve against the inner 80 tapered wall of the casing and thus it is that the split sleeve is caused to grip and hold the lead in writing position. The split sleeve is attached to a member which is capable of being moved endwise of the 85 pencil, and it is this split sleeve which has the passage therethrough leading to the magazine in which the leads are stored. The split sleeve is also provided with means for frictionally gripping the lead, so that 90

when the split sleeve is moved forward to clamp the lead through the frictional engagement therewith, the lead will be moved forward, and thus projected through the end of the pencil, and after it is so projected, then the split sleeve clamps and holds it in writing position. Associated with this split sleeve is a gripping device which grips the lead when the split sleeve is retracted, so that the split sleeve can move along the 100 lead to get a new frictional grip thereon whereby when the sleeve moves forward, the new length of lead will be projected from the end of the pencil. This split sleeve is moved back and forth in one embodiment of the invention by a screw. The 105

screw for moving the split sleeve may be located at the lower end of the magazine for the leads, in which case, the casing forming the magazine is capable of being turned 5 relative to the tapered end of the pencil for the purpose of moving the tapered end of the pencil and the split sleeve relative to each other. This screw may be located at the upper end of the magazine, in which 10 case, an inner casing is provided extending the full length of the magazine, which inner casing is attached to the split sleeve, so that when the inner casing is moved endwise, the split sleeve will move therewith for the 15 purposes stated above. Instead of using a screw for moving this inner casing, I may use a cap which is moved in one direction by a spring, and the other by the pressure of the thumb, thus producing a mechanical 20 pencil of the punch type.

Referring more in detail to the drawings, I have shown my improved mechanical pencil as consisting of an outer casing 1 which is provided at the lower end thereof with a 25 tapered section 2 having an opening in its end for the lead 3 of the pencil. In Figures 1 to 3, inclusive, there is an inner casing 4 which forms a magazine for the leads. This inner casing 4 has a cone-shaped inner 30 end 5. This cone-shaped inner end is formed in a sleeve 6 which is threaded into the inner casing, so that the sleeve is rigidly connected to the inner casing 4. Attached to this sleeve 6 is a split sleeve 7. The 35 split sleeve 7 is split from the outer end thereof to a point indicated at 8 in the drawings. There is a passage 9 through this split sleeve which extends all the way from the magazine to the outer end of the split sleeve. The outer end of this split sleeve is tapered 40 at 10 so as to conform substantially to the inner tapered surface 11 of the tapered section 2 of the pencil.

The inner casing 4 is provided with a screw thread 12 at its upper end. Projecting into this inner casing is a sleeve 13 which is provided with a screw thread 14 adapted to mesh with the thread 12. The sleeve 13 has a central passage 15 therethrough. A 45 cap 16 frictionally engages the outer end of the sleeve and when removed, leads may be inserted through the passage 15 into the magazine in the inner casing 4. Thus it is that the magazine is replenished with 50 leads. The outer casing 1 has the extreme upper end thereof provided with an inwardly projecting flange 17. There is an annular groove 18 in the sleeve 13, and the inturned flange 17 engages said groove 18 and holds 55 the sleeve and cap 16 from endwise movement on the outer casing 1. Thus it is that when the cap is turned, it will turn the sleeve, and the sleeve through the threads thereon, meshing with the threads on the inner casing 4, will move the inner casing 4 endwise 60 in the outer casing. This endwise movement of the inner casing will also impart an endwise movement to the split sleeve which is rigidly attached thereto. The split end of the sleeve 7 frictionally engages the 65 lead 3, and therefore, when the split sleeve is moved forward through the turning of the cap 16, the lead will be carried forward through this frictional engagement until it projects beyond the end of the pencil. The 70 continued movement of the split sleeve, however, will bring the tapered end 10 thereof into contact with the inner tapered surface 11 of the tapered section 2 of the pencil, and this will cause the split sleeve to firmly grip 75 the lead and hold it against any pressure on the end of the lead outside of the pencil. When this split sleeve is retracted, means is provided for holding the lead so that the frictional engagement of the split sleeve on 80 the lead will yield, and thus it is that the split sleeve will move along the lead for a new frictional grip thereon. This is accomplished by means of gripping pawls or dogs 85 19. These dogs are in the form of fingers. 90 The dogs are mounted on a ring 20 which slips over the split sleeve and frictionally engages the same. The dogs extend partly into the recess between the split sections of the sleeve. Rigidly connected to the outer 95 casing is a member 21. This member 21 has a cone-shaped end 22. Attached to the member 21 is a sleeve 23 having an inwardly projecting shoulder 24. The inner ends of the dogs 19 are tapered at 25, and said dogs 100 are provided with shoulders 26 intermediate the ends thereof. When the parts are in the position shown in Fig. 1, the lead is clamped, and this is brought about by the movement of the split sleeve downward to this clamping position. During this endwise movement of the split sleeve downward, the dogs were carried along therewith until the shoulders 26 engage the shoulder 24 on the sleeve 105 23. This prevents further movement of the dogs, and it also tilts the dogs until they are entirely out of engagement with the lead. At least, they are moved to a point where they do not in any way grip or mar the lead. When the split sleeve is moved up to the 110 position shown in Fig. 2, these dogs 19 are carried along with the split sleeve until the tapered ends 25 of the dogs engage the cone-shaped end 22 of the member 21. When the dogs thus engage this cone-shaped member, 115 they will be tilted until the forward ends of the dogs engage the lead. This causes the lead to be gripped with sufficient tension so as to prevent the lead from moving with the split sleeve as the dogs are now held 120 against any further upward movement. Thus it is that the split sleeve will move along the lead in an upward direction, notwithstanding the slight frictional engagement thereon, until a new position is obtained 125 130

upon the lead, so that when the split sleeve is again moved forward, the lead will be carried along with it and projected from the end of the pencil.

5 In order to prevent the inner casing 4 from rotating when the cap and the sleeve carrying the screw are rotated, I have provided the member 21 with spaced arms 27. The sleeve 6 is also provided with spaced 10 arms 28. These arms are free to move endwise of each other. The arms 27 are stationary because they are rigid with the sleeve or member 21 which is fixed to the outer casing. Therefore, the arms 28 can 15 rotate when the screw rotates, and this will insure that the inner casing is moved endwise and not rotated when the cap 16 is turned.

In Figures 4 and 5 of the drawings, I have shown a slightly modified form of the invention, in that the screw for moving the split sleeve endwise is located adjacent the lower end of the pencil, and the lower end of the magazine, rather than at the upper end thereof. In this form of the invention, 25 there is no inner casing. The outer casing 1 forms the magazine for the leads, and has a sleeve 6 attached thereto provided with a cone-shaped recess 5 leading to a passage in the split sleeve 7. The split sleeve 7 is 30 threaded into the member 6. The dogs for holding the lead, and the split sleeve for frictionally engaging the lead and moving it forward and for clamping the lead when in writing position, are exactly the same as 35 in the construction shown in Figures 1 to 3, and therefore, similar reference letters have been applied to these figures. The sleeve 6, is, however, extended in the present form of the invention and provided with a 40 screw thread 29. The outer casing 1 is formed in two pieces. The lower section 1^a carries the tapered end section 2 of the pencil. This lower section 1^a is provided with a screw thread 30 on its inner face, which meshes with the screw thread 29. 45 When the cap which is now fixed on the outer casing 1 is turned, it will cause the sleeve 6 to rotate, and this will either move the screw 29 into or out of the screw 30 depending upon which way the cap is turned. Thus it is that the section 1^a is moved toward or away from the section 1. The split sleeve is fixed to the section 1, and therefore, will be moved toward and from the inner tapered 50 face 11 of the section 1^a.

The operation of the structure shown in Figures 4 and 5 for the feeding and clamping of the lead is precisely the same as that shown in Figures 1 to 3, the only difference 55 being that the split sleeve is moved relative to the tapered end section by a screw at the lower end of the magazine instead of by a screw at the upper end of the magazine.

In Fig. 6 of the drawings, I have shown a 60 slightly modified form of the invention

wherein the split sleeve is moved toward the tapered end of the pencil for feeding and clamping the lead by a cap at the upper end of the pencil, which cap slides lengthwise of the casing instead of rotating with the casing. This makes what is generally referred to as a punch type of pencil. In this form of the invention there is an outer casing 1 and an inner casing 4, as in the structure shown in Figures 1 and 2. At the tapered end of the pencil, there is a split sleeve 7 which is threaded into the member 6 which in turn is threaded into the inner casing 4. The lead is indicated at 3 in the drawings, and the holding dogs are indicated at 19. This portion of the pencil is precisely the same as that shown in Fig. 1, and the lead is fed and clamped in writing position by an endwise movement of the casing 4, the same as in Fig. 1. This endwise movement 70 of the casing 4, however, is accomplished in a different way. It is brought about by means of a cap 29' which has a sliding engagement with the casing 1 and is capable of 75 moving endwise thereon. A rack bar 30' is secured to the upper end of the inner casing 4. The rack bar 31 is secured to the cap 29'. These rack bars both mesh with a gear 32 pivoted at 33 in the outer casing 1. It will readily be seen that when the cap is 80 pressed down as viewed in Fig. 6, it will turn the gear 32 and the turning of the gear 32 cooperating with the rack bar 30' will move the inner casing upward. When the rack bar 31 moves in the other direction, then the casing 4 is moved downward. A 85 spring 34 is placed in the end cap, and bears at one end against a slotted partition 35 through the slot in which the rack bars 30' and 31 pass. This spring is provided with a series of curved portions intermediate its ends, so that it is a tension spring normally forcing the cap 29' upward as viewed in Fig. 6. This movement of the cap upward causes a movement of the inner casing 4 downward, and this clamps the lead, but it feeds the lead forward before the lead is clamped. When a new length of lead is desired, the cap 29' is forced down by hand 90 pressure, and as the cap slides down the outer casing, it will retract the inner casing, drawing the split sleeve back from the inner tapered end of the pencil. It is at this time that the lead is held from movement by the dogs 19 and the split sleeve will move up on the lead and obtain a new frictional grip thereon, so that when the cap is released and the spring moves the cap upward, it will cause the lead to be fed forward and to be clamped in writing position. In this form of the pencil, owing to the partition 35, the lead is placed in the split sleeve by inserting the same therein from the open end of the pencil when the split sleeve is withdrawn from clamping position.

While I have shown and described a specific arrangement of dogs for preventing the lead from being retracted; when the split sleeve is moved away from the end of the casing for getting a new feeding grip on the lead, it will be understood that other schemes may be used for preventing the movement of the lead with the split sleeve.

It is obvious that minor changes in the details of construction may be made without departing from the spirit of the invention as set forth in the appended claims.

Having thus described the invention, what I claim as new and desire to secure by Letters Patent, is—

1. A mechanical pencil comprising a casing having a tapered end, a split sleeve in said casing having a passage therethrough for the lead, means for moving the sleeve in a direction toward the tapered end of the casing for projecting the lead to writing position and for clamping the lead for holding the same in writing position and for retracting the sleeve so as to release said clamping means, said sleeve having means for frictionally gripping the lead, and devices cooperating with said sleeve for holding the lead from movement when the sleeve is retracted.

2. A mechanical pencil comprising a casing having a tapered end provided with an inner tapered surface, a split sleeve having the ends thereof tapered and adapted to engage the inner tapered surface of the end of the pencil so that said split sleeve is forced into gripping contact with the lead, said sleeve having a passage therethrough for the lead and means for frictionally gripping the lead, and means for moving said split sleeve so as to project the lead into writing position and for causing said split sleeve to clamp and hold the lead in writing position.

3. A mechanical pencil comprising a casing having a tapered end provided with an inner tapered surface, a split sleeve having the ends thereof tapered and adapted to engage the inner tapered surface of the end of the pencil so that said split sleeve is forced into gripping contact with the lead, said sleeve having a passage therethrough for the lead and means for frictionally gripping the lead, means for moving said split sleeve so as to project the lead into writing position and for causing said split sleeve to clamp and hold the lead in writing position, and means cooperating with said split sleeve whereby when said split sleeve is retracted, the lead is held from movement so that said split sleeve obtains a new frictional grip upon the lead.

4. A mechanical pencil comprising a casing having a tapered end, a split sleeve in said casing having a passage therethrough for the lead, said split sleeve having means for frictionally gripping the lead, means for

moving the sleeve in a direction toward the tapered end of the casing for projecting the lead to writing position, said means for moving the sleeve including a screw thread, and devices for turning said screw thread for moving said split sleeve into and out of contact with the tapered end of the casing for clamping the lead for holding the same in writing position.

5. A mechanical pencil comprising a casing having a tapered end, a split sleeve in the casing having a passage therethrough for the lead, said split sleeve having means for frictionally gripping the lead, means carried by the casing and engaging the lead in the split sleeve when the split sleeve is moved away from the tapered end of the pencil for holding the lead so that the sleeve will move along the lead, and means for moving said split sleeve toward the tapered end of the pencil for projecting the lead into writing position and for clamping said lead in writing position.

6. A mechanical pencil comprising a casing having a tapered end, a split sleeve in the casing having a passage therethrough for the lead, said split sleeve having means for frictionally gripping the lead, means carried by the casing and engaging the lead in the split sleeve when the split sleeve is moved away from the tapered end of the pencil for holding the lead so that the sleeve will move along the lead, and means for moving said split sleeve toward the tapered end of the pencil for projecting the lead into writing position and for clamping said lead in writing position, said last-named means including cooperating screw threads, which, when rotated, force the split sleeve into engagement with the tapered end of the pencil and positively hold said split sleeve in engagement therewith so that the lead is firmly clamped in writing position.

7. A mechanical pencil comprising a casing having a tapered end, a split sleeve in said casing having a passage therethrough for the lead, said split sleeve having means for frictionally gripping the lead, means carried by the casing for engaging the lead and holding the lead from movement with the sleeve through said frictional engagement of the sleeve with the lead when the sleeve is retracted, said lead engaging means being released from the lead when the sleeve is moved forward so that the lead is moved with the sleeve through the frictional engagement of the sleeve with the lead, and means for moving said split sleeve toward and from the tapered end of the pencil for feeding the lead forward, and into engagement with the tapered end of the pencil for clamping the lead in writing position.

In testimony whereof, I affix my signature.

ROBERT H. INGERSOLL.
